Primary Examiner — Mark A Goodwin*(74) Attorney, Agent, or Firm* — Philip L. Bateman(57) **CLAIM**

The ornamental design for a cable bracket, as shown and described.

DESCRIPTION

FIG. 1 is a front, top, and left side perspective view of a cable bracket showing my new design;

FIG. 2 is a front, bottom, and right side perspective view thereof;

FIG. 3 is a top plan view thereof;

FIG. 4 is a front elevation view thereof;

FIG. 5 is a right side elevation view thereof;

FIG. 6 is a bottom plan view thereof;

FIG. 7 is a front, bottom, and right side exploded perspective view of a cable bracket and a single clip. The clip is shown in broken lines for illustrative purposes only and forms no part of the claimed design; and,

FIG. 8 is front, bottom, and right side assembled perspective view of two cable brackets stacked within a double clip, attached to an overhanging joist with nails, and holding two electrical cables. The clip, joist, nail heads, and cables are shown in broken lines for illustrative purposes only and form no part of the claimed design.
